UNITED STATES PATENT OFFICE.

BENJAMIN A. GRAMM, OF CHILLICOTHE, OHIO.

CONTROLLING MECHANISM FOR AUTOMOBILES.

No. 823,522.

Specification of Letters Patent.

Patented June 19, 1906.

Application filed November 17, 1905. Serial No. 287,891.

To all whom it may concern:

Be it known that I, BENJAMIN A. GRAMM, a citizen of the United States, residing in Chillicothe, in the county of Ross and State 5 of Ohio, have invented certain new and useful Improvements in Controlling Mechanism for Automobiles, of which the following is a description, reference being had to the accompanying drawings.

10 My invention relates to improvements in controlling mechanisms for automobiles; and the object of my invention is to provide means for interlocking the parts of such controlling mechanism, so as to prevent stripping 15 the gears and such untoward results which are liable to follow an improper sequence of operation of the parts.

In the drawings illustrating the principle 20 of my invention and the best mode now known to me of applying that principle, Figure 1 is a side elevation of my new mechanism. Fig. 2 is a sectional view on line A A of Fig. 1, the levers c and d being thrown to the right; and Fig. 3 is a sectional plan view 25 on line B B of Fig. 1.

In the V-shaped side frame a is mounted a shaft b, upon which are pivotally mounted two levers, the clutch-lever c and the shift-gear lever d. The ends of the side frame a 30 are connected by a curved strap or brace e, secured to the side frame by the bolts e', upon which are mounted also the two curved straps f and g. The strap e is formed with the notches h, i, and j, adapted to receive the shift-gear lever d. When the shift-gear lever d is in the notch i, the automobile is geared 35 for low speed and when it is in the notch j the machine is geared for high speed. To reverse the machine, the shift-gear lever d 40 is thrown into the notch h. As is clearly shown in Fig. 3, the shift-gear lever d travels in the slot between the straps e and f, while the clutch-lever c travels in the slot between the straps f and g.

45 In lugs k, projecting from the side frame a, is pivotally mounted a shuttle-bar m, adapted to swing beneath the middle strap f. This shuttle-bar m is formed with a notch n at one end. When the clutch-lever c is 50 thrown to the right in Fig. 1, it releases the clutch mechanism of the automobile, and in this releasing position it is opposite the notch n of the pivoted shuttle-bar m. This gives room for the operator to throw the shift-gear lever d out of that one of the notches 55 h i j in which it is at that time engaged and

to move it into either one of the other two notches. While the shift-gear lever d is traveling between the notches, the clutch-lever c is locked in its releasing position in the notch 60 n of the shuttle-bar m. The shift-gear lever d having been engaged with the proper notch the clutch-lever b is thrown to the left in Fig. 1, thereby throwing the clutch mechanism of the machine into operative position. In 65 this position of the clutch-lever c the shuttle-bar m is thrown over toward the shift-gear lever d, thereby locking the latter in position.

From what has been stated it is obvious 70 that in my new controlling mechanism it is impossible to move the shift-gear lever while the clutch mechanism is in operative position, and it is also impossible to throw the clutch mechanism into operation while the speed or direction of the machine is being changed. 75

What I claim is—

1. In a controlling mechanism for automobiles, the combination of a supporting-frame; a power-controlling lever mounted therein; a speed-controlling lever mounted in said 80 frame; and a swinging bar pivotally mounted in said frame between said levers, said levers lying on opposite sides of said bar, said bar being formed with a notch in one of its ends shaped to receive one of said levers and holding one of said levers locked while the other is free to move; the movement of one of said levers shifting said bar toward the other lever to lock the same. 85

2. In a controlling mechanism for automobiles, the combination of a supporting-frame; a pair of coöperating side members mounted therein; a speed-controlling lever fulcrumed in said frame between said side members the face of one of said side members opposed to 90 said lever being formed with notches in which said lever is adapted to rest; a power-controlling lever fulcrumed in said frame between said side members; a movable shuttle-bar which lies between said levers and is shifted 95 by the movement of one of said levers to lock the other lever against simultaneous operation. 100

3. In a controlling mechanism for automobiles, the combination of a supporting-frame; a pair of side members mounted in said frame; a speed-controlling lever mounted in said frame between said side members, the face of one of said side members opposed to said 105 levers being formed with notches in which said lever is adapted to rest; a power-controlling lever mounted in said frame between 110

said side members; and a shuttle-bar formed with a notch adapted to receive said power-controlling lever and to lock the same against one of said side members; said shuttle-bar being shifted by the movement of one of said levers toward the other of said levers to lock the same against simultaneous operation.

4. In a controlling mechanism for automobiles, the combination of a supporting-frame provided with side members; a pair of levers mounted in said frame between said side members; a locking shuttle-bar which is

interposed between said levers and coöperates with one of said side members to lock against it that one of said levers lying between said shuttle-bar and coöperating side members; said shuttle-bar being by the movement of one of said levers shifted toward the other of said levers to lock said other lever against simultaneous movement.

BENJAMIN A. GRAMM.
